(57) **CLAIM**

The ornamental design for a jewelry accessory, as shown and described.

DESCRIPTION

FIG. 1 shows a perspective view of a jewelry accessory; FIG. 2 shows an exploded perspective view of the jewelry accessory showing how the components of the jewelry accessory may come apart;

FIG. 3 shows a top planar view of the jewelry accessory; FIG. 4 shows a bottom planar view of the jewelry accessory; FIG. 5 shows a left side view of the jewelry accessory; FIG. 6 shows a right side view of the jewelry accessory; FIG. 7 shows a front view of the jewelry accessory; and, FIG. 8 shows a rear view of the jewelry accessory.

The broken lines shown in the Figures show portions of the jewelry accessory which form no part of the claimed design.
